UNITED STATES PATENT OFFICE

171,667

PENDANT OR SIMILAR ARTICLE

Virgil Uldric Speed, Orient, Iowa

Application April 8, 1953, Serial No. 24,402

Term of patent 3½ years

(Cl. D45—17)

To all whom it may concern:

Be it known that I, Virgil Uldric Speed, a citizen of the United States of America, residing at Orient, Adair County, Iowa, have invented a new, original, and ornamental Design for a Pendant or Similar Article, of which the following is a specification, reference being had to the accompanying drawings forming a part thereof.

I claim:

The ornamental design for a pendant or similar article, as shown.

VIRGIL ULDRIC SPEED.
